UNITED STATES PATENT OFFICE.

EDGAR F. M. SPIES, OF BALTIMORE, MARYLAND.

NECKTIE-HOLDER.

1,261,640.

Specification of Letters Patent.

Patented Apr. 2, 1918.

Application filed September 19, 1917. Serial No. 192,042.

To all whom it may concern:

Be it known that I, EDGAR F. M. SPIES, a citizen of the United States, residing at Baltimore city, in the State of Maryland, 5 have invented certain new and useful Improvements in Necktie-Holders, of which the following is a specification.

This invention relates to a holder for neck-ties for men's wear, the neck-tie bow 10 or other tie-formation being shaped on the holder itself, so that both the holder and the neck-tie together may be lifted from the collar-button when the wearer desires, and subsequently replaced on the collar button 15 without unloosening or disturbing the neck-tie bow formation.

The invention is illustrated in the accompanying drawing in which,—

Figure 1, is a front view of one form of 20 the holder device,—the proportion as to size of parts being immaterial.

Fig. 2, is a top view of same showing the curved formation.

Fig. 3, is a horizontal section view on the 25 line 3—3 of Fig. 1.

Fig. 4, shows a section on the vertical line of a collar-button of the several parts embracing shirt neck-band, a collar, and the neck-tie holder.

Fig. 5, shows a front view of the holder and a tie when in its first position of the 30 operation of inserting a tie through the holder to form a bow.

Fig. 6, shows the holder and the tie in 35 the next stage of fashioning the tie.

Fig. 7, shows another stage, and

Fig. 8, shows the final bow-shape of the tie.

The tie-holder may be made of any suitable sheet material, such as sheet-metal or 40 sheet-celluloid, something that will retain its form but which will yield or flex.

The thin base-plate 9, is to go at the front of a man's neck and is curved from end to 45 end to conform with the collar when the latter is in position about the neck. The base-plate at its center, and lower part has a downwardly-projecting portion, 10, which is provided with an opening 11, adapted to 50 take over the head 12, of an ordinary collar-button which holds a collar 13, to the front part of a shirt neck-band 14.

The base-plate 9, also has two parallel vertical slots 15, one being at each of two

opposite sides of said collar-button opening 55 11. A horizontal bar 16, extends across this opening on the outer side of the plate and the bar is loose or free to move up and down with its ends 17, passed through the vertical slots 15, from the front side to the rear 60 where said ends are bent substantially Z-shape to form lugs, as shown in Fig. 3, to retain the movable bar from disconnecting. When the base-plate 9, is in position, and the collar-button head 12, projects laterally, 65 as shown in Fig. 4, the movable bar 16, will move down and engage behind the protruding collar-button head 12, and thereby the said bar 16, will prevent the neck-tie holder from accidentally slipping off the collar- 70 button.

The base-plate further has a slot or opening 18, extending longitudinally relative to the base plate 9, above the collar-button opening 11; said opening 18 allows one end 75 19, of the neck-tie to be passed from the front into and drawn through the opening as seen in Fig. 7, when forming or fashioning the tie.

A bar 20, extends along the upper side 80 of and closes the opening or slot 18, and said bar is concave along its upper edge. The slot or opening 18, is of a length to accommodate the widest four-in-hand tie that may be used in that during the threading of the 85 tie through the holder one end thereof will be passed up in front of the central portion 10, then through the slot or opening 18, as shown in Fig. 7, and finally said tie-end will be extended over and down in front of 90 the bar 20, and passed through the knot as in Fig. 8.

At each end the base-plate has a slot 23, with a vertical bar 24, at the outer side of said slot, and the outer vertical edge 21, of this 95 bar 24, is guarded at both its upper and lower ends by projecting or extended lugs 22, so that when the tie is folded around the bar 24, the lugs 22, will prevent the same from slipping vertically on the bar either 100 upwardly or downwardly. The projecting lugs are therefore guard-lugs to prevent vertical displacement of the tie-fold about the bar.

It will be observed that the end 19, of the 105 neck-tie that has been drawn through the horizontal opening 18, as seen in Fig. 7, can be folded forward and then downward at

the front to cover and conceal the top-bar 20, of the base plate, and to complete the tie-formation, as indicated in Fig. 8, which latter shows the final view of the tie and holder. The opposite ends of the tie-loop, and the lugs on the ends of the holder would be concealed from view when the holder is worn on a turn-down or turn-over collar.

Obviously the lugs 22, can be made of different shape and relatively much smaller than shown in the drawing; and the proportion in size of other parts may be varied to suit the style of collar and the width of neck-tie that may be in vogue.

15 The bar 16, may be raised to release its engagement with the collar-button head 12, and then both the holder and tie formed thereon may be removed.

20 From the foregoing description the structure of the tie-holder, and the method of placing the tie fabric on the holder, and producing at the front the bow, loop, or other tie-formation will be understood.

Copies of this patent may be obtained for five cents each, by addressing the "Commissioner of Patents, Washington, D. C."

Having described my invention what I claim is,—

A neck-tie holder comprising upper and lower longitudinal bars,—the upper edge of the upper bar being concaved midway between its ends, an end cross-bar near each end of and connecting the two longitudinal bars said end cross-bars being guarded at both the upper and lower ends by projecting lugs, inner cross-bars also connecting the said longitudinal bars and forming a slot at the inner side of each end bar and also forming a longitudinal slot between the upper and lower bars and the lower longitudinal bar being provided with movable means for engaging a collar button.

30 In testimony whereof I affix my signature 35 in the presence of two witnesses.

EDGAR F. M. SPIES.
